UNITED STATES PATENT OFFICE.

WILLIAM H. BAILEY, OF GARY, INDIANA.

BLAST-FURNACE TOP.

1,193,750.

Specification of Letters Patent. Patented Aug. 8, 1916.

Application filed December 18, 1915. Serial No. 67,549.

To all whom it may concern:

Be it known that I, WILLIAM H. BAILEY, a citizen of the United States, and resident of Gary, in the county of Lake and State 5 of Indiana, have invented certain new and useful Improvements in Blast-Furnace Tops, of which the following is a specification.

My invention relates to blast furnaces, and has particular reference to a novel top 10 construction therefor.

An object in the present construction is to provide a top for blast furnaces which shall be of simple construction, easily built in place and supported independently of the 15 masonry shaft for the blast furnace.

As a reason for the last mentioned object, it is well known that the masonry shaft of a blast furnace is subject to considerable longitudinal movement under expansion and 20 contraction, and if the masonry lining for the top is directly connected to the masonry shaft and the masonry top is anchored in any manner by structural work, as is usually necessary, the top, or shaft, will be distorted 25 shortly after being blown in.

An object, therefore, in the present construction is to provide means whereby the top, including its lining, are supported independently of the masonry shaft, thus giving 30 freedom to the shaft for whatever expansion is necessary.

The invention will be more readily understood by reference to the accompanying drawings, in which the figure is a vertical 35 sectional view through the upper portion of a blast furnace to which my improvement has been applied.

In the drawings it will be seen that I provide a shell 10 for the blast furnace 40 shaft, and a masonry lining 11, the lining and shell terminating at the point 12. A plate 13, in the form of an annular, laterally projecting shelf, is secured to the shell 10 by means of an angle 14, the outer edge of 45 the shelf being braced by members 15 secured to the shell at a lower point. The shell, or covering, 16, for the top is secured to the outer edge of the shelf 13, this covering being lined by masonry 17, as is usual 50 in such cases. It will be noted that the

masonry rests on the shelf 13, and that both the covering 16 and the lining 17 are supported by the shell 10 of the blast furnace shaft and are located entirely outside of the shell. This permits of an increase in the size 55 of the top and provides for efficient distribution of the burden through the hopper 18 and the bell 19. These elements are not detailed as they form no part of the present invention.

It will be noted that while the top is not connected to the blast furnace shaft, it is nevertheless rigidly secured to the shell without danger of being blown off if a slip occurs; also that the construction permits 65 of the use of a masonry lining for the top without lessening the space within which distribution may be made and providing ample space for the location of downcomers 70 in the top, if desired.

I claim:

1. In a blast furnace, the combination of a shaft, including a shell and a masonry lining, a shelf secured to said shell and projecting outwardly from the shell, and a masonry 75 top built on and supported by said shelf, substantially as described.

2. In a blast furnace, the combination of a shaft, including a masonry lining and a metallic shell, an annular plate secured to 80 said shell near the top thereof and projecting laterally and outwardly therefrom, a top shell secured to said shelf and a masonry lining for the top built on said shelf, substantially as described.

3. In a blast furnace, the combination of a shaft, comprising a metallic shell and a masonry lining, an annular shelf projecting outwardly from said shell, and a hemispherical masonry top resting on and supported by said shelf, substantially as described.

Signed at Gary, Indiana, this 4th day of December, 1915.

WILLIAM H. BAILEY.
